(57) **CLAIM**

We claim the ornamental design for a control housing, as shown and described.

DESCRIPTION

FIG. 1 is a perspective view of our control housing;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof, showing additional environmental structure.

The dashed lines in the figures represent environmental structure and form no part of the claimed design. All other surface(s) or portion(s) of our designs not shown in the figures or otherwise described in the specification form no part of the claimed design.
